CLAIM

The ornamental design for a circular tubular frame for a desk fan, as shown and described.

DESCRIPTION

FIG. 1 is a front perspective view of the circular tubular frame for a desk fan of the present invention;

FIG. 2 is a rear perspective view showing the circular tubular frame for a desk fan of the present invention;

FIG. 3 is a front elevational view of the circular tubular frame for a desk fan;

FIG. 4 is a rear elevational view of the circular tubular frame for a desk fan;

FIG. 5 is a side elevational view of the circular tubular frame for a desk fan;

FIG. 6 is a side elevational view of the opposed side of the circular tubular frame for a desk fan;

FIG. 7 is a bottom view of the circular tubular frame for a desk fan; and,

FIG. 8 is a top view of the circular tubular frame for a desk fan. The broken line showing of the fan grill, hub and base is included for the purpose of illustrating environmental structure and forms no part of the claimed design.
